TRAVEL TRAILER

William C. Schmelzer, 118 Briar Heath Circle,
Dayton, Ohio 45415

Filed Aug. 5, 1970, Ser. No. 24,321

Term of patent 14 years

Int. Cl. D12—03

U.S. Cl. D14—3

FIG-1

FIG-2

FIG-3

FIG-4

FIG-5

FIG-6

FIG. 1 is a perspective view of a travel trailer embodying my design;

FIG. 2 is a side view thereof;

FIG. 3 is an end view thereof;

FIG. 4 is a top view thereof;

FIG. 5 is an opposite side view thereof;

FIG. 6 is an opposite end view thereof.

I claim:

The ornamental design for travel trailer, substantially as shown and described.
